ABSTRACT OF THE DISCLOSURE

This charged particle generator produces a highly concentrated beam of ions. An electron gun, an ion chamber, an ion accelerator, and an electrostatic lens are cascaded and provided with aligned apertures whereby this ion beam is produced, focused, and directed in a well-controlled manner.

FIELD OF INVENTION AND BACKGROUND

Prior art methods of calibrating quadrupole mass spectrometers utilize the Nier gun, which lacks control over the ion beam which it generates.

The invention is a novel device for the formation, control and focusing of an ion beam. A primary object of the invention is to provide a device which minimizes energy distribution spread of the ion beam. Such spread is a cause of error in the calibrating of quadrupole mass spectrometers. The invention is of particular utility for such calibration.

Another object of the invention is to provide a novel device for generating a high-intensity low-energy positive ion beam having mono-energetic properties. The term "mono-energetic" is employed to designate a single electron volt population at one energy level.

Another object of the invention is to provide a convenient source for a low-energy plasma beam, plasma being understood to be a mixture of ions and electrons.

GENERAL DESCRIPTION OF DRAWINGS

For a better understanding of the invention, together with other and further objects, advantages and capabilities thereof, reference is made to the following detailed description of the drawings hereto annexed.

In the drawings, FIG. 1 is a perspective view, partially broken away for purposes of exposition, showing a preferred embodiment of charged particle generator in accordance with the invention; FIG. 2 is a view of similar character with reference to a modified form of the invention; and FIG. 3 is a circuit schematic, showing representative electrical potentials applied to the FIG. 1 embodiment.

DETAILED DESCRIPTION OF THE INVENTION

The charged particle generator ion source herein shown is unique in that it is formed with coaxial elements and has a well defined electrical region in the physical area in which ion formation occurs. The ion source of the present invention consists of an arrangement of cylindrical elements located along a common central axis as shown in FIG. 1. Each element contains an aperture for the passage of and control of emitted particles. The ion beam produced is discretely defined by a narrow energy distribution about a selected energy. The ion source utilizes electron bombardment to produce ions and an electro-

2

static lens to converge the ion beam. The ion beam thus generated can be controlled in energy range from less than from (1) electron volt to more than two thousand (2,000) electron volts and has a current capacity of zero to one microampere. The charged particle generator of the type herein described must be operated in a partial vacuum where relatively long mean free paths prevail, which implies an operation vacuum of 10^{-5} torr or greater. The limit of travel of a charged particle through a gaseous medium, prior to collision, is related to the mean free path of the molecules composing the medium. Temperature of the surrounding medium is not a critical factor for this application.

The charged particle gun of either FIGS. 1, 3 or FIG. 15 2 should be placed in a vacuum chamber 9 (FIG. 3) and evacuated to a pressure of 10^{-5} torr or greater. The number of ions formed is a function of the ion chamber pressure; hence, improved ionization efficiency is obtained by admitting a small amount of gas into the ion chamber. 20 This improvement is the result of an increase in the density of neutral particles in the ion chamber which increases ionization due to the increased probability of particle collision. The quantity of gas admitted should not increase the ion chamber pressure more than a decade above the 25 surrounding pressure of the chamber (10^{-5} torr or so). The correct quantity of gas may be calculated theoretically but, in practice, the quantity is determined empirically. The correct quantity of gas and ion chamber pressure are determined to exist at the point where the greatest ion current is obtained.

The elemental gas feed into the ion chamber will determine the type of ion formed and emitted from the chamber. The types of elemental gases used in this invention and their applications are argon for surface cleaning (i.e., electron multiplier applications) and nitrogen for rarefied atmospheric simulations. Atmospheric air has also been introduced into the chamber, producing a steady flow of mixed positive ions.

The energy of the emitted ions is largely determined by 40 the electrical potential applied to the ion chamber; thus, the electrical potentials applied to the remaining elements of the invention must be related to the ion chamber's potential. Ions formed by the collision of electrons with neutral particles within the ion chamber will have at the point of formation an energy of approximately 0.1 electron volt. This energy is derived from the thermal energy of the neutrals plus that energy obtained from the collision. In addition, the ions will possess, at the point of formation, 45 a potential energy equivalent to the electrical potential existing at the point of formation. Since all points within the ion chamber are at the same potential, the chamber is electrically closed and, thus, all ions formed within the ion chamber will have the potential of the chamber which, when added to the thermal and collision energies, will 50 yield a group of ions that form a mono-energetic ion beam.

The filament 11 (FIG. 1) as here employed is of rhenium. In one successfully operative embodiment of the invention it was operated with a current of 5.5 amperes at 55 2.5 volts. Either alternating current or direct current may be employed. A tungsten filament is acceptable. The filament is biased negatively with respect to the ion chamber by 30 to 150 volts, in order to assist in controlling the flow of electrons between the filament and the ion chamber. The electron emission control electrode 12 (FIG. 1) 60 is in the nature of a metallic thimble or cylinder having

one end closed with a central aperture. Its function is to control the rate of flow of electrons from the filament to the ion chamber. Therefore, it operates in a manner analogous to the control grid of a vacuum tube or cathode ray tube. The flow of electrons depends on the size of the aperture, the physical spacing between the filament and the electron accelerator 13 (FIG. 1) and the biasing potentials. The electron control grid is provided with a variable bias arrangement so that its voltage may be varied between zero and such negative voltage as cuts off electron flow.

The electron accelerator element 13 is in the form of an inverted thimble or cylinder having one end closed, coaxial with and somewhat larger in diameter than the element 12 (FIG. 1). It is also provided with a central aperture. The electron accelerator element 13 has two functions. First, it accelerates the flow of electrons into the ion chamber 14 and second, it prevents the escape of ions into the surrounding vacuum. That is to say, electrons emitted by the filament are caused by the electron accelerator to be accelerated away from the filament and through the apertures of the emission control grid and the electron accelerator into the ion chamber. The potential of the accelerator should be from 1 to 5 volts positive with respect to the ion chamber. Increased currents can be obtained by providing two electron accelerators, as shown in FIG. 2 and later described herein.

Next adjacent the electron accelerator is the ion chamber element which is cylindrical in form and closed at both ends. Except for central apertures the ion chamber is provided with a removable gas inlet cap 16 (FIG. 1). In the above-mentioned embodiment of the invention the length of the ion chamber was approximately fifteen times the distance from the filament to the near end of the ion chamber.

In operation, gas is introduced into the ion chamber through the gas inlet and the internal pressure of the chamber is increased approximately a decade or more above the surrounding vacuum pressure. Parenthetically, it is reiterated that the entire structure of FIG. 1 is positioned within a vacuum chamber (not shown). The internal pressure of the ion chamber 14 (FIG. 1) during operation is approximately 10^{-4} torr. Ionization occurs in the chamber due to the collisions between electrons emitted by the filament and the gas molecules. The probability of collision between an electron and a neutral gas molecule is related to the mean free path travelled by the electron and the amount of gas present. The high probability of ionization within the chamber is due to the density of the gas contained within the chamber, the relatively short mean free path of the gas molecules and the length of the chamber. Disposed in front of the ion chamber 14 is an ion accelerating element 17 (FIG. 1). The remaining elements illustrated in FIG. 1 are electrostatic focusing elements comprising a focusing electrode 18 (FIG. 1) and a ground plane focusing arrangement shown as elements 19, 20 (FIG. 1).

The operating potentials indicated in FIG. 3 are furnished by way of illustration and not of limitation and they were employed with one successful embodiment of the invention.

Element: Voltage

17	-170
11	-125
20	Ground
The wall of 14	8
13	10
18	12
19	Ground
12	0 to -40

In this embodiment the filament 11 was operated at 5 amperes from a 2 volt supply.

The FIG. 2 embodiment differs from that of FIG. 1

in that it has a second electronic accelerating element 15 (FIG. 2).

It should be noted that the invention comprises, essentially, an electron gun, an electrostatic focusing system, and an ion chamber, all having registering apertures which define a straight path for the generation, focusing, and direction of an ion beam.

While there has been shown and described what is at present considered to be the preferred embodiment of the invention, it will be understood by those skilled in the art that various changes and modifications may be made therein without departing from the scope of the invention as defined by the appended claims.

I claim:

1. A charged particle generator yielding a mono-energetic ion beam comprising in combination:
a substantially closed cylindrical conductive ion chamber having axially aligned apertures in opposing ends, said chamber being maintained at a first electrical potential;
an electron source filament axially aligned with said ion chamber for generating free electrons for injection through one of said apertures and into said ion chamber, said filament being biased negatively with respect to said ion chamber;
a cylindrical electron control electrode mounted coaxially about said filament, said electrode having one end closed with a central aperture therein and being axially aligned with said ion chamber to control the flow of electrons from said filament to said ion chamber;
an electron accelerator having a central aperture axially aligned with said ion chamber and mounted between said ion chamber and said control electrode, said electron accelerator being biased positively with respect to said ion chamber;
means for introducing a gas into said ion chamber wherein ions having a uniform energy are formed within said chamber;
electrostatic lens means for focusing ions exhausted out of said ion chamber and into said electrostatic lens means;
an ion accelerator having a central aperture therein mounted between said ion chamber and said electrostatic lens means in axial alignment therewith, said ion accelerator being biased negative with respect to said ion chamber thereby exhausting ions formed in said ion chamber through the other of said ion chamber apertures and into said electrostatic lens means; and
said ion chamber, electron source filament, control electrode, electron accelerator, ion accelerator, and electrostatic lens means mounted along a common longitudinal axis wherein the ions formed in said ion chamber flow in a direct path to said electrostatic lens whereby the ions are focused and directed therefrom in a beam with minimum spread.

2. The combination as claimed in claim 1 in which said electron accelerator is a cylinder having one end closed with a central aperture therethrough, said cylinder being larger in diameter than said electron control electrode and mounted coaxially therewith wherein said electron accelerator accelerates the flow of electrons into said ion chamber and further prevents the escape of ions from the aperture of said ion chamber;
variable bias means interconnected with said electron control electrode wherein said control electrode may be varied from zero to such negative voltage as to prevent electron flow to said ion chamber; and
said electrostatic lens further having a focusing electrode biased at a higher potential than said ion chamber.

3. The combination as claimed in claim 1 in which said electron accelerator further comprises a split anode.
